UNITED STATES PATENT OFFICE.

DE VER H. WARNER, OF BRIDGEPORT, CONNECTICUT, ASSIGNOR TO THE WARNER BROTHERS COMPANY, OF SAME PLACE.

DESIGN FOR A STUD OR BUTTON FOR GARMENT-SUPPORTERS.

SPECIFICATION forming part of Design No. 33,771, dated December 25, 1900.

Application filed March 21, 1900. Serial No. 9,615. Term of patent 14 years.

To all whom it may concern:

Be it known that I, DE VER H. WARNER, a citizen of the United States, residing at Bridgeport, in the county of Fairfield and State of Connecticut, have invented and produced a new and original Design for Studs or Buttons for Garment-Supporters, of which the following is a specification.

My invention relates to a new and original design for studs or buttons for garment-supporters, of which the following is a specification, reference being had to the accompanying drawings.

Figure 1 of the drawings is a front elevation of a stud and support embodying my new design, and Fig. 2 is a vertical sectional view of the same.

As shown in the drawings, my new design consists in a stud or button for a garment-supporter having a cylindrical shank and an enlarged head having a circular periphery. The stud is mounted on a looped base or support, as shown.

The essential features of my new design consist in a head, the top central portion of which is dome-shaped, slightly projecting, as is seen at *a*, with a flat edge *b*, and having a flange *c* sloping upward and outward from the said central portion and forming a concave rim surrounding the dome-shaped center.

Having described my invention, what I claim as new, and desire to secure by Letters Patent, is—

The design for a stud or button for garment-supporters, substantially as herein shown and described.

In witness whereof I have signed my name to this specification in the presence of two subscribing witnesses.

DE VER H. WARNER.
